THURE LARSSON, OF WORCESTER, MASSACHUSETTS, ASSIGNOR TO NORTON COMPANY,
OF WORCESTER, MASSACHUSETTS, A CORPORATION OF MASSACHUSETTS.

MUFFLE TUNNEL KILN.

Application filed January 28, 1921, Serial No. 440,810. Renewed January 7, 1924.

To all whom it may concern:

Be it known that I, THURE LARSSON, a citizen of the United States of America, residing at Worcester, in the county of Worcester and State of Massachusetts, have invented certain new and useful Improvements in Muffle Tunnel Kilns, of which the following is a full, clear, and exact specification.

My invention relates to an improvement in the construction of tunnel kilns and more particularly to one of the muffle type having a combustion chamber disposed longitudinally of the kiln.

Muffle tunnel kilns, such as are commonly employed for high temperature work, have consisted of a longitudinal chamber through which ware-conveying cars may pass and combustion chambers on either side which supply the heat to the ware being treated. They have been built for the burning of solid, liquid or gaseous fuel, and with various arrangements for carrying off the gaseous products of combustion longitudinally or transversely through flues in the kiln wall without coming into contact with the ware which is being fired.

Such kilns, as heretofore constructed, have the disadvantage that the heat radiating from the rear of the muffle is not properly directed to the ware for efficient utilization, and that no adequate provision has heretofore been made for regulating the temperature conditions within the cooling zone of the kiln or for giving the ware a uniform or desired heat treatment. In one type of kiln, the combustion chamber has double walls providing air ducts which communicate with passages within the car body and with the kiln chamber for the circulation of air therethrough, but such circulation must depend upon differences in density of the air caused by differences of temperature. When the kiln is in operation this force will be inadequate to produce uniformity of heat conditions and will tend to concentrate hot air in the top of the kiln chamber. As a consequence, the ware in different positions in the car may not be uniformly fired or the temperature may not be sufficiently controlled in all portions of the kiln for the proper treatment of ware which requires careful firing. Hence, there may be variations in structure, quality and appearance, which it is very important to avoid in the manufacture of articles, such as grinding

wheels, which must be carefully inspected and tested before use.

It is accordingly an object of my invention to overcome such disadvantages and to heat a tunnel kiln chamber more uniformly than is possible with such prior constructions and generally to render the tunnel kiln operation more efficient by utilizing heat heretofore wasted through the walls of the kiln or drawn off from the muffle chamber and to provide a kiln in which the temperature conditions may be readily regulated in different portions thereof.

More specifically, it is an object of this invention to utilize the heat which radiates from the combustion chambers in a direction away from the ware by providing heat conducting air ducts passing in the rear of the combustion chambers and then adjacent the ware to conduct heat thereto.

It is a further object of this invention to circulate such heated air positively to heat the inner roof wall of the kiln chamber and the car top to provide further direct transfer of heat to the ware and more uniform conditions within the kiln.

Further objects of my invention are to effectively and evenly cool the ware within the cooling zone of the kiln by a forced circulation of air through a conduit surrounding the ware and to utilize such portions of the circulating air as may be desired to support combustion of the gases within the muffle chamber.

With these and other objects in view, as will be apparent from the following disclosure, my invention resides in the combination of parts set forth in the specification and as covered by the claims appended hereto.

A specific embodiment of my invention is illustrated by the accompanying drawings in which:

Figure 1 is a horizontal cross section, partly broken away, showing the combustion chambers, the vertical heating conduits and the kiln cars;

Fig. 2 is a horizontal cross section through the top of the tunnel kiln, on the line 2-2 of Fig. 3, showing the transverse conduits;

Fig. 3 is a vertical section of the tunnel kiln, partly broken away, through the combustion chambers and the heating chamber along the line 3-3 of Fig. 1 looking in the

direction of the arrows, and showing kiln cars in position on the tracks;

Fig. 4 is a cross section of the tunnel kiln along the line 4—4 of Fig. 1, showing a 5 kiln car in the cooling zone; and

Fig. 5 is a cross section of the combustion zone of the tunnel kiln along the line 5—5 of Fig. 1, showing a kiln car in position on the tracks, fans connected with the outlet 10 ends of the combustion chambers and a fan connected to the outlet ends of the hot air 15 conduits.

In accordance with my invention, I provide a tunnel kiln with a combustion chamber 15 disposed longitudinally of the heating zone, which radiates heat from its front face directly toward the ware and from another side to an air conduit which is adapted to circulate the heated air to another portion 20 of the kiln where it may transmit its heat to the ware. I preferably so design this kiln construction that the air conduit may form a continuous passage whereby air may be 25 positively drawn through the same by a fan or other suitable mechanism. In the specific form illustrated, this heated air is passed across the top of the kiln for transmitting heat downwardly and then through passages in the kiln car beneath the ware. The air 30 conduit therefor may have a substantially helical path surrounding the space through which the ware travels, the pitch of the helix being provided by an oblique arrangement of the conduit on any or all sides of the kiln 35 chamber.

Since previous methods of cooling the ware in the cooling zone have been deficient, I propose furthermore to substantially surround the cooling zone with an air conduit 40 which has refractory walls adapted to conduct heat from the tunnel kiln, and I preferably utilize a construction similar to that of the heating zone wherein the air may be drawn progressively through a continuous 45 conduit around the car passage, and preferably through the refractory body of the car itself. In order to assist in regulating the temperature in the heating zone, I may pass desired amounts of heated air from the air 50 conduit to the combustion chamber at spaced points. Furthermore, air may be drawn from the outside of the chamber both into the air conduit in either zone and into the combustion chamber in the heating zone, in 55 order that the temperature conditions may be more fully regulated.

In accordance with the specific embodiment of my invention shown in the accompanying drawings, I construct a pair of 60 foundation walls 1 parallel to each other and having a suitable space between them provided with a floor along which are laid the tracks 2 for supporting the ware-conveying cars. The space between said founda- 65 tion walls is of such size and shape in cross

section that it will fit the body of the kiln car closely but permit it to run freely along the tracks without interruption. The outer side walls 11 and 12, which are built upon the foundation walls 1 and joined at the top 70 by the outer roof wall 13, are held together by suitably spaced steel plates 14 and cross rods 15. To insulate the kiln, a layer 16 of suitable material of low heat conductivity, such as diatomaceous earth, is placed over 75 the top of the roof wall and a similar filling is placed in longitudinal spaces 17 within the side walls. This general construction is the same throughout the length of the kiln.

As one simple arrangement for heating 80 the kiln, I provide an inner roof wall 22 parallel to the outer roof wall 13 but spaced from it, and at each side of the kiln chamber the thin vertical walls 20 and 21 of suitable refractory material, which are spaced 85 from the outer kiln walls and extend the length of the kiln. These vertical walls connect the foundation walls 1 with the refractory inner roof wall 22, thus forming an inner heating or kiln chamber for the passage 90 of the kiln cars, as shown, particularly in Figs. 1 and 5. This roof wall is suitably formed either of refractory plates or bricks keyed together.

Between the inner walls 20 and 21 of the 95 heating chamber and the outer side walls 11 and 12 of the kiln, in that portion of the kiln AB which is to constitute the hot zone, and parallel to them, are constructed the intermediate refractory walls 25 and 26 which 100 are joined to the inner sides of the roof wall 22 extended at the top, as illustrated, and to horizontal partitions 29 and 30 at the bottom, which connect them with the walls of the heating chamber 20 and 21 respectively, the 105 members 32 being spaced between the vertical walls to strengthen the construction. These walls and partitions, thus constructed, form a longitudinal combustion or muffle chamber 34 on each side of the heating chamber. The vertical walls 25 and 26 are spaced 110 from the outer kiln walls 11 and 12 to form air spaces in the rear of the combustion chambers, and, as shown, vertical partitions 35 are provided to form separated conduits 115 36 for the circulation of heated gases, as will be explained. The inner roof wall 22 is tied to and made integral with the outer wall 13 by means of spaced partitions 37 which provide a plurality of conduits 39 between 120 the inner and outer roof walls 22 and 13, which open into the vertical conduits 36, the actual construction of the kiln parts being such as is well understood by ceramic kiln 125 engineers.

A similar construction may be employed in the cooling zone BC of the kiln, except that the combustion chambers are omitted. Here, the inner walls 20 and 21 are separated from the outer walls to form a cooling 130

air space. As shown, vertical partitions 40 similar to partitions 35 in the heating zone are provided to form vertical conduits 41 and 42 which open into conduits 43 above the inner roof wall 22 in this zone, which are formed similar to conduits 39 by partitions 44.

In order to provide for a circulation of air through the conduits around the cooling and heating zones, I connect these together so as to form a continuous passage, or, as illustrated, several parallel passages adapted to convey the air in a multiple relationship. If it is desired to heat the car bottoms by this circulated air, I may employ the construction shown. In this case, each car 50, which may be otherwise constructed in the usual form, is provided with transverse passages which communicate with the vertical conduits in the kiln walls. To this end, the refractory body 51 of the kiln car may be built to provide a plurality of separate transverse conduits 52 located closely beneath the top of the car, which is suitably constructed for supporting the ware. On each side of the car and above the openings to the conduits 52 is a longitudinal flange 53 equal to the length of the car body which forms a sand seal with the trough 49 on the kiln wall. A similar seal beneath the openings is formed by the flange 54 on the car and the sand-trough 55 on the kiln foundation walls 1. These seals insure a minimum of leakage of air from the conduits 52 into the kiln chamber. It of course is understood that a sufficient number of similar kiln cars is provided so that when placed end to end they will extend throughout the length of the kiln.

In order that the car passages may communicate with the vertical conduits in the heating zone, the lower ends of the conduits 36 connect with short horizontal flues 56 and 57, formed by the foundation walls 1, the vertical partitions 58 and the horizontal partitions 29 and 30 respectively, which enter the heating chamber. In the cooling zone, the vertical conduits enter the heating chamber through the openings 60 in the side walls 20 and 21, at such points as to connect with the conduits 52 in the tops of the kiln cars when they are in position on the tracks. In order to form a continuous or substantially helical air passage of the various conduits and flues described, I may arrange any of the sets of passages obliquely. In the particular form illustrated, I have shown the transverse passages in the cars so arranged that they connect each conduit 56 with the fourth conduit 57 beyond it and on the opposite side of the heating chamber, whereby air may pass helically through a set of four parallel passages.

If it is not desired to take air directly

from the kiln chamber, the first four vertical conduits 41 in the side wall 11 are not connected with the heating chamber but have entrance openings 61 at their lower ends, which communicate with the outside of the kiln for the introduction of fresh air. At the diagonally opposite end of the tunnel kiln the last four vertical flues 36, in the side wall, do not communicate with the heating chamber but are connected through the outlets 62 and the air duct 63 to an exhaust fan 64, whereby the air may be forced to circulate at a desired rate.

At suitable points along the outer sides of the kiln walls, I provide openings 65 which pass through the wall 1 and the partitions between the vertical conduits 36 into the combustion chambers. Burners 66, which may be water cooled to prevent them from being destroyed by the temperatures attained in the combustion chambers, are inserted through said openings 65 into the combustion chambers and are connected with suitable oil or gas fuel supply pipes 67. Air in desired quantities may also be introduced into the combustion chambers through regulatable openings 68 (see Fig. 3) closed by removable and adjustable caps 69. For the introduction of air directly from the hot air conduits to the muffles, I may provide a set of suitably spaced conduits 71 (only one being shown, in Fig. 3) which pass from the transverse passageway 39 to a point outside the kiln, and a similar set of conduits 72 opening into the muffle chamber 34. A regulatable communication between conduits 71 and 72 may be established by means of suitable mechanism, such as the slide valve 73 having a groove 74 adapted to connect the conduits when the valve is in one position and to be shut off from such communication by a solid portion 75 of the slide which covers opening 71 when the slide is in a second position. In order to provide for further variation in the temperature curve, conduits 76 having movable caps 77 may be spaced at desired intervals for conducting air from the external atmosphere into the helical air conduit. At the opposite ends of the combustion chambers from where the burners are located, outlets 78 are provided which lead to the exhaust fans 79 for carrying off the products of combustion.

In the operation of the tunnel kiln, which has been described as representative of kilns embodying my invention, the ware which is to be fired is loaded onto kiln cars in suitable containers, care being taken that none projects beyond the kiln car or will become displaced during the passage of the car through the kiln. The cars thus loaded are run into the kiln, from the end A, as cars of fired ware are withdrawn from the opposite end. These cars butt closely against each other, as shown in Fig. 3, so that the four diagonal flues in

- the car at the end C of the kiln, and in each successive car thereafter, will, in conjunction with the car next to it, connect the set of four flues in the kiln wall 21 opposite to it 5 with the next set of four flues in the opposite wall 20. There are thus formed four essentially continuous flues passing around the heating and combustion chambers in a substantially helical path. Air drawn in 10 through the openings 61 passes upward through the first four vertical conduits 41, across through the first four transverse flues 43 in the top of the kiln, downward through the first four vertical conduits 42, then 15 through the horizontal conduits into the obliquely disposed passages 52 in the kiln cars; thence into the four vertical conduits 41 beyond those through which it entered the kiln originally, and thus continuously 20 throughout the length of the tunnel kiln until it has reached the opposite end where it is drawn out by the exhaust fan. The other exhaust fans likewise draw air into the combustion chambers and withdraw 25 products of combustion therefrom, in accordance with the locations of the various valves, as is determined by the nature of the ware to be treated and the heat curve desired.
- 30 The air which is drawn through the helical flues in the walls of the cooling zone BC is heated by the residual heat contained in the ware which has been fired and when drawn into the combustion chambers absorbs but little heat from the flames in being brought up to the temperature of ignition. That portion of the air which continues on through the helical flues is heated up as it passes through the vertical flues 35 in contact with the combustion chambers and gives off this heat to the heating chamber as it passes through the transverse conduits in the roof and through the tops of the kiln cars, thus bringing these portions 40 of the heating chamber to a temperature closely approaching that of the side portions of the heating chamber which are heated directly by radiation from the combustion chambers themselves.
- 45 It will be apparent to those skilled in the art that my invention may be adapted in various other ways and to the construction of high and of low temperature tunnel kilns, but it is to be understood that such adaptations and modifications are to be considered as broadly comprehended and included by the following claims.
- Having thus described my invention, what I claim as new and desire to secure by Letters Patent is:
- 50 1. A tunnel kiln comprising outer walls defining a kiln chamber for conveying ware therethrough, a combustion chamber within the kiln arranged longitudinally thereof, means providing an air conduit adjacent the 55 combustion chamber, and means for positively circulating air through said conduit to absorb heat from the combustion chamber and transfer it indirectly to the ware.
2. A tunnel kiln comprising side and connecting walls spaced apart for the passage of ware therethrough, a combustion chamber arranged within the kiln to heat the ware, structural means defining a heat conducting conduit having a refractory wall portion exposed to the heat of the combustion chamber and another wall portion for transmitting heat directly to the ware, and means to circulate air through said conduit. 70
3. A tunnel kiln comprising kiln walls defining a passage for conveying ware therethrough, a combustion chamber arranged longitudinally within the kiln to heat the ware, structural means defining an air conduit on the side of the combustion chamber opposite from the ware, said conduit having an extended wall from which heat may be radiated directly to the ware, and means to circulate air positively through said conduit. 75
4. A tunnel kiln comprising kiln walls defining a passage for the conveying of ware therethrough, a combustion chamber disposed longitudinally within said kiln, structural means defining a continuous passage through which air may circulate alternately adjacent a muffle wall and the ware for transferring heat indirectly thereto, and means for effecting a positive circulation of air through said passage. 80
5. A tunnel kiln comprising outer kiln walls arranged for the passage of ware therethrough, a combustion chamber disposed longitudinally within the kiln and separated from said outer walls, means, including partitions between the outer kiln wall and the combustion chamber, forming an air conduit for transferring heat from the rear of the combustion chamber indirectly to the ware, means for drawing air through said air conduit, and means for supplying fuel to the combustion chamber and for withdrawing products of combustion therefrom. 105
6. A tunnel kiln comprising inner side and connecting walls spaced apart to form a kiln chamber for the passage of ware, a combustion chamber having front and rear refractory walls, the front wall being in common with a portion of one of said kiln 110 chamber walls for transmitting heat directly to the kiln chamber, and means including outer walls cooperating with said rear wall to form a hot air conduit adjacent the combustion chamber and with one of said inner kiln walls to form a continuation of said conduit for transmitting heat indirectly to the ware through the inner kiln wall. 120
7. A tunnel kiln comprising a founda- 125

- tion, side walls and a top wall constructed and arranged for the passage of ware therethrough, a longitudinal combustion chamber within the kiln and spaced from its 5 walls for radiating heat to the ware and rearwardly to an air space and structural means including a thin wall adjacent the ware which cooperate with said kiln structure to form an air chamber communicating 10 with said air space for conveying heat therefrom to said wall and indirectly thereby to the ware.
8. A tunnel kiln comprising walls constructed for the passage of ware therethrough, a longitudinal combustion chamber within said kiln for heating the ware, structural means defining an air conduit surrounding the ware-passage and combustion chamber, and means for positively circulating 15 air through said conduit to transfer heat from the combustion chamber to the ware.
9. A tunnel kiln comprising walls forming a longitudinal heating chamber for the 20 passage of ware therethrough, a combustion chamber disposed longitudinally of the kiln, and structural means defining a continuous air conduit extending transversely around said heating and combustion chamber in a substantially helical path.
10. A tunnel kiln comprising walls defining a kiln chamber for the passage of ware therethrough, a combustion muffle within the kiln for heating the ware, structural 25 means defining an air passage substantially surrounding the cooling zone of the kiln and means for positively circulating air therethrough.
11. A tunnel kiln comprising walls defining a kiln chamber for the passage of ware therethrough and having a continuous helical air conduit surrounding the ware chamber in the cooling zone of the kiln for absorbing heat from the ware, a combustion 30 muffle disposed longitudinally of the kiln in the heating zone, means for introducing fuel to the combustion chamber and for withdrawing the products of combustion therefrom, and means for circulating air through said continuous conduit.
12. A tunnel kiln comprising walls defining a kiln chamber for the passage of ware therethrough, a combustion chamber within the heating zone of said kiln, structural 35 means defining a conduit in the cooling zone of the kiln, means for positively circulating air through said conduit, and regulatable means for admitting air from the external atmosphere to separated portions of the conduit.
13. A tunnel kiln comprising walls spaced apart for the passage of ware therethrough, a combustion chamber longitudinally disposed within the heating zone of the kiln, 40 an air conduit within the cooling zone of the kiln having a valve controlled inlet opening into said chamber, and means for drawing air into the combustion chamber or by-passing it to a separate exit.
14. A tunnel kiln comprising walls spaced apart for the passage of ware therethrough, a combustion chamber disposed longitudinally within the kiln, structural means comprising inner walls forming a kiln chamber and a substantially helical air conduit around said kiln chamber and adjacent said combustion chamber to transfer heat from the latter to the former, and regulatable means for introducing air into said conduit to vary the 45 temperature thereof.
15. A tunnel kiln comprising walls defining a kiln chamber for the passage of ware therethrough, structural means forming a conduit for circulating air around said kiln chamber in the cooling zone thereof, a combustion muffle disposed longitudinally of the kiln, said air conduit having a passage communicating with the muffle chamber, means for drawing air through said air conduit and into the muffle chamber and for withdrawing products of combustion from the latter, and regulatable means for admitting air from the external atmosphere to spaced portions of said conduit.
16. A tunnel kiln comprising outer walls defining a passage for conveying ware therethrough, a combustion chamber arranged longitudinally within the kiln chamber, means forming an air conduit adjacent the kiln chamber walls in one part and adjacent the combustion chamber in another part, means for regulatably drawing air through said conduit to transfer heat from the combustion chamber to the kiln chamber, and means providing regulatable inlet openings from said air conduit to the combustion chamber at separated points.
17. A tunnel kiln comprising walls forming a passage for conveying ware therethrough, a combustion chamber arranged longitudinally within the kiln for heating the ware, a series of ware-conveying cars within said passage, each car having a refractory body provided with transverse conduits therethrough, structural means defining air conduits within the kiln having openings communicating with said transverse conduits, and means for positively circulating air through said conduits.
18. A tunnel kiln comprising walls forming a passage for conveying ware therethrough, a muffle longitudinally disposed within said kiln for heating the ware, a series of ware-conveying cars within the passage, each car having a refractory body provided with a transverse passage therethrough, structural means forming a series of air conduits passing adjacent the combustion chamber for absorbing heat therefrom, said conduits having openings com-

municating with the transverse passages in the cars, and means for positively circulating air through said passages and conduits.

19. A tunnel kiln comprising walls defining a kiln chamber for the conveyance of ware therethrough, a combustion chamber disposed longitudinally of the kiln, means, including a series of ware-conveying cars having refractory bodies provided with
- 5 horizontal transverse passages therethrough, forming a substantially helical conduit surrounding the kiln chamber, and means for positively circulating air through said conduit.
- 15 20. A tunnel kiln comprising a foundation, outer side walls and a top wall, refractory members within the kiln forming a combustion chamber spaced from said outer kiln walls and located on each side of the
- 20 ware passage, intermediate partitions extending from the outer members of the combustion chambers to the outer side walls and forming upright air flues, an inner refractory wall beneath and spaced from said top wall and partitions coacting therewith to form conduits which connect the upper ends of the upright flues, and means forming with said flues a continuous passage for the circulation of air to transfer heat from
- 25 the rear of the combustion chamber to the inner refractory wall and indirectly therethrough to the ware.
21. A tunnel kiln comprising outer walls defining a passage for conveying ware therethrough, a combustion chamber arranged longitudinally adjacent a side wall of the kiln chamber and spaced therefrom, a ware-conveying car within the kiln having a refractory body thereon and transverse passages therethrough, structural means cooperating with the kiln wall and the combustion chamber defining air conduits in the
- 30 rear of said chamber and providing a communication from the air conduits to the passages in the car body, further structural means providing a continuation of said air conduit and having a refractory wall through which heat may be radiated to the ware within the kiln chamber, and means for circulating air positively through said conduits and car passage.
- 35 22. A tunnel kiln comprising a foundation, outer side walls and a roof, intermediate walls cooperating with said outer side walls to form upright air flues, a refractory wall spaced from the roof wall and cooperating therewith to form a transverse air flue connecting the upright flues, refractory walls spaced from the intermediate side walls and cooperating therewith and with the top refractory wall and the foundation walls of the kiln to form a longitudinal combustion chamber on each side of a kiln chamber, which transfers heat directly through its front wall to the ware and through its rear wall to the upright flues, a kiln car within the kiln chamber comprising a refractory body having oblique transverse passages therethrough, the foundation walls being provided with passages connecting the upright air flues with the air passages in said kiln car and thus forming a continuous substantially helical air passage around the kiln chamber, and means for drawing air through said passage.
- 40 23. A kiln car adapted for carrying ware through a tunnel kiln comprising a car platform and a refractory top thereon having diagonally disposed, horizontal conduits therethrough, substantially as described.

Signed at Worcester, Massachusetts, this 27th day of Jan., 1921.

THURE LARSSON.
